United States Patent Office

Des. 183,958
Patented Nov. 25, 1958

183,958

SWIVEL-CHAIR

Joseph Burger, Brooklyn, N. Y.

Application January 17, 1958, Serial No. 49,292

Term of patent 3½ years

(Cl. D15—1)

FIG. 1

FIG. 2

FIG. 3

FIG. 4

FIG. 5.

Fig. 1 is a side elevational view of a swivel-chair embodying my design;

Fig. 2 is a front view thereof;

Fig. 3 is a bottom view thereof;

Fig. 4 is a top view thereof; and

Fig. 5 is a rear view.

The characteristic features of my design reside in the portions shown by means of full lines in the drawing.

I claim:

The ornamental design for a swivel-chair, substantially as shown and described.
